CLAIM

The ornamental design for a sensor, as shown and described.

DESCRIPTION

FIG. 1 is a front perspective view of a sensor showing our new design in an unassembled state;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a front perspective view of the sensor of FIGS. 1-7 shown in an assembled state;
FIG. 9 is a front view thereof;
FIG. 10 is a rear view thereof;
FIG. 11 is a left side view thereof;

FIG. 12 is a right side view thereof;
FIG. 13 is a top view thereof;
FIG. 14 is a bottom view thereof;
FIG. 15 is a front perspective view of the front portion of the sensor of FIGS. 1-7 shown in isolation;
FIG. 16 is a front view thereof;
FIG. 17 is a rear view thereof;
FIG. 18 is a left side view thereof;
FIG. 19 is a right side view thereof;
FIG. 20 is a top view thereof;
FIG. 21 is a bottom view thereof;
FIG. 22 is a front perspective view of the rear portion of the sensor of FIGS. 1-7 shown in isolation;
FIG. 23 is a front view thereof;
FIG. 24 is a rear view thereof;
FIG. 25 is a left side view thereof;
FIG. 26 is a right side view thereof;
FIG. 27 is a top view thereof; and,
FIG. 28 is a bottom view thereof.

The broken line oval within the shaded area on the front face of the sensor forms no part of the claimed design. The broken lines immediately adjacent to the shaded areas represent the bounds of the claimed design and form no part thereof. The broken lines depicting the remainder of the sensor form no part of the claimed design.
